UNITED STATES PATENT OFFICE.

WALTER S. MOODY, OF LYNN, MASSACHUSETTS, ASSIGNOR TO THE GENERAL ELECTRIC COMPANY, OF NEW YORK.

DESIGN FOR A TRANSFORMER-CASE.

SPECIFICATION forming part of Design No. 25,762, dated July 7, 1896.

Application filed April 1, 1896. Serial No. 585,823. Term of patent 14 years.

To all whom it may concern:

Be it known that I, WALTER S. MOODY, a citizen of the United States, residing at Lynn, in the county of Essex, State of Massachusetts, have invented and produced a new and original Design for Transformer-Cases, of which the following is a specification.

Referring to the accompanying drawings, Figure 1 is a perspective view showing in elevation the front of the design, and Fig. 2 is a perspective view of the rear of the design.

This design relates to a casing for electrical transformers, and embraces in its general outline a body portion 1, having oval corners, sides, and bottom, and a base portion 2, of smaller area than the body portion 1, and also having oval corners and edges.

The leading or characteristic feature of the design consists in the shape or configuration, as shown in the accompanying drawings.

At the top of the body portion 1 is a band-like portion 3, which extends along one side of and nearly across the front of the body portion 1, and is formed with rounded corners and edges. At the side of the casing the band 3 is provided with a depending hook-like projection 4. Upon the top of the casing is located a portion 5, having rounded corners and a double narrow band-shaped edge 6, with a central projecting lip-like portion 7 and an elevated flat portion 8, at the rear and on the top of the cover, somewhat in the shape of a parallelogram. The portion 5 has a lip-like portion 9 at one side project-

ing over the depending hook-shaped projection 4.

The configuration of the casing at its rear is shown in Fig. 2, which is similar to that in Fig. 1, with the addition of tapering projections 10, enlarged at their lower ends and 40 having U-shaped slots 11, open at their lower end and connected by a narrow strip 12 raised above the surface of the rear of the body portion 1. The band already described at the top of the body portion 1 on the front of the 45 casing extends across the rear of the body portion at the top, and has projecting therefrom two rectangular projections 13, with U-shaped openings 14 open at their lower end.

The depending hook-shaped projection 15 50 is provided on the opposite side of the casing from that of the depending hook-shaped projection 4, already described, and a lip 16, which projects above the depending hook-shaped projection similarly to the lip on the 55 opposite side of the casing. Above both of said lips are short cylindrical portions 17, provided with oval tapering projections 18.

What I claim is—

The design for a transformer-casing, as 60 herein set forth.

In witness whereof I have hereunto set my hand this 30th day of March, 1896.

WALTER S. MOODY.
